UNITED STATES PATENT OFFICE.

OTTO SPAHR, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

GAS-BURNER.

1,242,487.

Specification of Letters Patent.

Patented Oct. 9, 1917.

Application filed December 31, 1913. Serial No. 809,597.

To all whom it may concern:

Be it known that I, OTTO SPAHR, a citizen of the United States, and a resident of Philadelphia, county of Philadelphia, State 5 of Pennsylvania, have invented certain new and useful Improvements in Gas-Burners, of which the following is a specification.

My invention relates to gas burners and more especially to gas burners for self-heating gas irons and the like and has for its 10 object to produce a superior burner of this kind, one which will insure complete combustion, without odor or loss of heat, of the gas used and which will be suitable for use 15 with any kind of gas, whether natural or manufactured. It is a further object of my invention to produce such a gas iron burner structure that the flame jets issuing from the flame apertures thereof will be affected 20 to a minimum degree by excess air in the gas, by external atmospheric drafts or by other influences tending to extinguish the flames. Other objects will be specifically 25 pointed out or will otherwise appear in the following description of the embodiment of my invention shown in the accompanying drawings.

In said drawings Figure 1 is a side elevation of a gas iron with parts in section and 30 with my improvement applied thereto; Fig. 2 is a cross-section thereof on the line 2—2 of Fig. 1; Fig. 3 is a rear end elevation; Fig. 4 is an enlarged cross-section of the burner and Fig. 5 is a detail view of a 35 slightly different form of burner.

In the drawings 10 represents the hollow body of the iron which may be provided with the usual cover 11 movable relatively thereto and having the customary operating 40 handle 12 of any desired type for manipulating the iron, the said cover being locked in position on the body in any suitable manner as by means of a locking lever 13. The side walls of the body may also be cut away 45 at the top to form ventilating apertures 14 along the sides and the rear wall 15 may be similarly cut away at the top to form ventilating apertures 15^a at the rear end of the iron. As shown the body 10 is provided 50 with air inlet channels 16 which extend through the solid bottom 10^a and have their inner ends communicating with the interior of the body in any suitable manner as for instance through the medium of a well or recess 17 formed in said bottom 10^a and ex-

tending lengthwise thereof as shown in Fig. 1. In the form illustrated in Figs. 1, 2 and 3, the burner comprises a tube 18 having its forward end externally screw-threaded as indicated at 19 and its rear end internally screw-threaded to receive the externally screw-threaded end of the mixing tube 20. The said mixing tube has its free end provided with the customary nipple 21 having the usual air inlets 22 and upon which the usual customary flexible hose or tube for connecting the iron with a source of fuel supply is adapted to be slipped. A lock nut 23 is located on the externally screw-threaded end of the tube 20 and is arranged to be screwed into engagement with the end of the tube 18 whereby the said tubes 18 and 20 are firmly locked together. The tube 18 is formed with a double series of radially extending jet apertures 24 located on opposite sides of the longitudinal center line of said tube 18 and being of relatively large size and having their inner ends covered with netting, gauze, or the like 25. As shown in the 80 illustrated example the netting or gauze 25 is in the form of a continuous tube which is inserted into the tube 18 and is held in position therein in any suitable manner as by friction, it being understood that 85 other forms of netting or gauze may be used or that the apertures 24 may be separately covered with individual sections of netting or gauze on the inside if this should be desired.

When connected with the body the tube 18 of the burner extends through an opening 26 located in the rear wall 15 and has its screw-threaded forward end 19 screwed into a screw-threaded recess 19^a formed in the forward end of said body. The jet apertures 24 are thus all located within the body as shown in Fig. 1, and the mixing tube 20 is located exteriorly thereof and is preferably inclined relatively to said body when viewed from the front or rear end. The opening 26 and the recess 19^a are so located that the tube 18 will be located above and in registry with the well 17 or the like, when the burner is connected with the body as described above. In addition to this the rear wall 15 is provided with an enlarged recess 26^a which surrounds the opening 26 and is adapted to receive the lock nut 23 when the burner is in its operative position. With 110

this construction the rear end surface of the iron is free from projections and the nut 23 is protected so that undesired interference or tampering therewith is absolutely prevented.

With the present construction the gas before issuing through the jet apertures 24 is broken up or disintegrated by the netting or gauze 25 and a double series of comparatively large flames are produced through and around which the air entering through the channels 16 into the well 17 or the like is forced to pass, thus insuring perfect combustion and a maximum heat effect with a minimum of fuel. The said large flames are caused to firmly adhere to the burner tube 18 even with said large apertures 24 as the interstices of the netting 25 are smaller than said apertures and said netting thus provides an effective foundation or hold for said flames and maintains them in the desired operative relation to the burner. In addition to this the roots of the various flame jets will be located closely adjacent to the netting or gauze 25 and will in consequence be protected by the walls of the jet apertures 24 so that the said jets of flame are not likely to become extinguished and are affected to a minimum degree by excess air in the gas, and by external atmospheric drafts or the like. The said gauze or netting also serves to filter the gas, thus resulting in a clean flame and making it possible to use the iron with either manufactured or natural gas without change or substitution and furthermore absolutely prevents backfire. The construction shown and described also permits use of the iron with any type of gas at any pressure without necessitating any special adjustment or the substitution of any special parts. By constructing the netting or gauze 25 in the form of a tube or the like the same may be manipulated to bring different parts thereof into registry with the jet apertures 24 so that as one part of the netting or gauze becomes clogged or unserviceable, another clean part may be adjusted over the said apertures, thus doing away with the necessity for frequent cleaning or renewals of the gauze or netting.

By screwing the tube 20 into the tube 18 a shoulder 20^a is formed in said burner tube 18 against which the one end of the netting, gauze or the like 25 may abut. With this construction the inner surface of said netting or gauze 25 is substantially flush with the inner surface of the tube 20 so that a free path for the fuel into said burner tube 18 is provided. In other words the end of the netting, 25, with this arrangement does not form an obstruction in the path of the fuel and in consequence friction is reduced to a minimum. An additional shoulder 20^b may be formed in any suitable manner in the upper portion of the tube 20, the di-

ameter of the combined tubes 18 and 20 thus increasing in successive steps from the inlet end on and still further insuring a proper forward travel of the fuel by removing all obstructions from its path and consequently reducing friction to a minimum.

Experience with burners of the type included in the present case has shown that the fuel as it enters the burner tube when the latter is cold will force and compress itself into the extreme forward end of the burner tube in Fig. 1 thus ordinarily tending to exert a back pressure at least at the first few apertures 24. With the present construction, as the burner tube becomes heated and thereby heats the accumulated fuel therein, the said fuel expands rearwardly along the entire tube 18 until it reaches the shoulder 20^a through the interstices or meshes of the gauze 25. This shoulder in combination with the forward portion of the iron which closes the forward end of the tube 18 confines this expanded fuel and as new fuel is continually added and becomes similarly expanded, preserves an equal pressure or in other words equalizes the pressure at all of the apertures 24. Perfect and uniform flames are in this manner provided at each aperture 24 and result in a uniform or equal heating of the iron throughout.

In the burner shown in Fig. 5 the tubes 18^a and 20^a are made integral or in one piece instead of separately as are the tubes 18 and 20 in the first form, the two forms being otherwise identical.

Various changes in the specific forms shown and described may be made within the scope of the claims without departing from the spirit of my invention.

I claim:—

1. A burner for self-heating gas irons and the like comprising a horizontal burner tube having jet apertures located only in its lower half, a mixing tube arranged to screw into the one end of said burner tube and forming an annular shoulder therein, a lock-nut adapted to engage the end of said burner-tube whereby said burner and mixing tubes are locked together and foraminated means in said burner tube covering the inner ends of the said jet apertures and abutting against said shoulder whereby obstruction to the flow of the fuel is prevented.

2. A self-heating gas iron comprising a hollow body having an opening in its rear wall and an enlarged recess surrounding same, an apertured burner tube extending through said opening into said body, a mixing tube arranged to screw into one end of said burner tube and a lock nut adapted to engage the end of said burner tube whereby said burner and mixing tubes are locked together, said lock-nut being adapted to be received in said enlarged recess whereby the

said lock-nut is protected against interference.

3. A self-heating gas iron comprising a hollow body having an opening in its rear wall and an enlarged recess surrounding same, a burner tube extending through said opening and having a double series of radially extending jet apertures, a mixing tube arranged to screw into one end of said burner tube and forming an annular shoulder therein, a lock-nut adapted to engage the end of said burner tube whereby said burner and mixing tubes are locked together, said

lock-nut being adapted to be received in said enlarged recess whereby the said lock-nut is 15 protected against interference and foraminated means in said burner tube extending over the inner ends of all of said jet apertures.

In testimony whereof, I have hereunto 20 set my hand in the presence of two subscribing witnesses.

OTTO SPAHR.
